UNITED STATES PATENT OFFICE

ROBERT LAY HALLOCK, OF MOUNT VERNON, NEW YORK, ASSIGNOR TO SANITARY PUBLIC SERVICE CORPORATION, OF NEW YORK, N. Y., A CORPORATION OF DELAWARE

PAPER SEVERING AND DISPENSING MEANS

Application filed March 24, 1927. Serial No. 177,929.

This invention relates to means for severing and dispensing sheets of paper and kindred material and articles; and particularly to a cabined device for forming and dispensing, simultaneously, from a roll of paper, a series of towels or sanitary covers for toilet seats. An object of the invention is to provide a new means of automatically severing, as by the operation of tearing, strips of paper, or like material, from a longer strip or roll.

Another object is to provide a means for dispensing such articles that the article is at the same time formed.

Yet a further object is to provide a simple and compact device, economical to manufacture and practically fool-proof in operation, for automatically forming and dispensing a toilet-seat cover, and also in conjunction with a coin-slot mechanism to permit the dispensing of but one article on the introduction of one coin.

Other objects will be apparent as the description proceeds.

All these objects are accomplished by the means described in the following specification, and illustrated in the accompanying drawings, in which—

Figure 1 is a vertical side elevation and interior view of the device, attached to a wall; Fig. 2, a front vertical elevation similar to Fig. 1; Fig. 3, a more or less full-size detail view, showing the novel means of severing the material and of holding it firmly while being severed; Fig. 4, a sectional view taken through the plane 4—4 of Fig. 1; Fig. 5, a view of the surface of the female roller, developed into a plane; Fig. 6, a fragmentary view of the sheet of paper, showing where it is severed at each end and also the partially severed hole in the middle, this view also showing, necessarily, the positioning of the severing means on the surface of the male roller, after being developed into one plane.

Similar numerals refer to similar parts throughout the several views.

Attached to a wall 1, is a casing or cabinet 2, in which there is a multiple bearing-frame or support 3.

50 Rotatably mounted in the uppermost bear-

ing of support 3, is a shaft 4 supporting a roll of paper 5. This paper is some relatively-cheap tissue material, somewhat heavier than ordinary toilet paper, being moisture-absorbent to a proper degree. The roll is a 55 continuous strip of paper approximately equal in width to the widest part of an ordinary toilet seat.

On a forwardly placed bearing or shaft 6 is a female roller 7 made, for instance, of metal, or wood. The surface of this roller 7, when developed into one plane, is shown in Fig. 5. It has grooves representing one-half of the pattern (to be cut from the paper) super-imposed upon the other half. Thus, the groove 8, Figs. 5 and 6, is the part first used to sever the paper as the male member, hereinafter described, enters it. That portion of the hole of the seat cover represented by groove-portion 9 is next cut. By that time this roller 7 has made a complete revolution. The male member then enters the portion of the groove numbered 10, and so continuing around to slot 8, again severs or tears off the paper at the other end, thus forming the complete seat cover. 75

The lowermost shaft 11 rotatably supports a male roller 12, which is here shown as twice the diameter of its corresponding female roller 7, described above. The developed surface of the severing members of this roll 12 is identical, in position and shape, to the cuts 8, 9, and 10 in the paper illustrated in Fig. 6. 80

Roller 12 may be solid, or built up structurally as suggested in Fig. 4. The construction of the tearing members or knives on its surface is shown clearly in Fig. 3, the members being preferably steel strips 13 of L shaped cross-section, their bases secured over the surface of male roller 12, and their projecting edges projecting into the grooves of said roller as shown. 85

It should be noted that the edges of these severing members 13 need not be sharp; and they need not fit accurately into the grooves 8, 9, and 10 of roller 7. In fact, a reasonably loose fit is desirable, to enable the paper to be severed by a tearing action as distinguished from a shearing action. 95

A strip of rubber 14, or other yieldable 100

material, parallel to the contour of the knife member 13 is so positioned as to be in advance of its severing edge as the roller 12 revolves. The purpose of this is to hold the paper, or other sheet material, shown in Fig. 3 by a dot and dash line, firmly in place while being severed by member 13, as by a partial tearing and partial cutting action.

It will be observed that the pattern of the 10 cuts or tears to be made in the paper is such that each portion of each cut is substantially on a slant, thus permitting the severing of the paper to be made gradually along one or more lines, somewhat like the action of a 15 scissors. Other rubber strips may also be positioned concentrically around the surface of roller 12, as shown in Fig. 2.

Keyed at one end of shaft 6, Fig. 2, is a gear 15; also a crank handle 16. Meshing 20 with gear 15 is a second gear 17, twice as large, and keyed to the shaft 11 which rotates the male roller 12. Thus, two complete turns of crank 16 will rotate roller 7 twice, and roller 12 once, and will tear off and feed 25 from the roll of paper 5 one toilet-seat cover shaped as shown in Fig. 6.

In casing 2 is a coin slot 18, Figs. 1 and 2, into which a coin is introduced. It drops down through passage 19 to operate trigger 30 20 to release a lock 21 and 22, so that the two rollers and the paper roll may be free to revolve.

The course of the paper sheet through the mechanism is shown by a dot-and-dash line 35 numbered 5, Fig. 1, the toilet-seat cover finally emerging through a slot 23 in the casing 2.

It will be noted in Fig. 6 that the end cuts or tears of the paper, here numbered 8, do not 40 meet, there being a space 24 where the paper has not been severed. This is accomplished by having the knife blade 13 notched a similar amount, as shown in Fig. 2 by the same numeral 24. Thus, each toilet-seat cover is 45 held to its upper one, and when the crank 16 has been turned twice to completely cut and vend one cover, the seat cover hangs down through slot 23 and is held suspended by this small piece of paper which has not been 50 severed. The user then simply takes hold of exposed part of the cover and pulls slightly, tearing off this piece and releasing the cover from the rest of the paper.

Particular attention is directed to the 55 simple operation by this means of severing the paper. No expensive dies or knives, likely to dull and get out of order, are used. No accurate alignment of the severing members 60 is required to be maintained. Even an inaccurate fit between knife and groove, as shown in Fig. 3, will not prevent the severing action from taking place properly. And only 65 the rubber strips 14 hold the paper firmly in place while it is being severed. Thus the

means are new and simple, and a great advance in the art.

The invention produces a toilet-seat cover of the general nature disclosed in Fig. 6, it being adapted to be cut from a roll of paper 70 automatically at the same time it is vended from the machine and by the same operation of the user. It will be noticed that the hole in the center of the paper is not completely severed, a portion 25 between the ends of the 75 cut or tear remaining un torn. This portion is usually positioned in the front of the toilet-seat and the weight of the partly-torn flap drops down vertically, forming a bend across the portion 25, the lower portion of the flap 80 projecting into the water of the toilet. When the toilet is flushed, the suction action of the water is strong enough to automatically carry away the entire toilet-seat cover.

It is to be understood that the present disclosure is for the purpose of illustration only, and that the invention is not limited thereto. To those skilled in the art, many modifications of the invention will be readily apparent, and it will also be obvious to such skilled 90 persons that part of the device may be used without other parts thereof, many such combinations of the parts readily suggesting themselves. Where the machine is to dispense a paper towel, the flap forming knives 95 are omitted. Therefore, it should be, and is to be distinctly understood that for a definition of the limitations of the invention, reference must be had to the appended claims.

Having now described the invention, what 100 is claimed as new and for which Letters Patent of the United States is desired, is:

1. Tearing means including a roller member formed with a grooved pattern in its surface, a co-operating roller member with a projecting pattern on its surface corresponding to the grooved pattern of the first member, the two members being mounted on parallel axes and driven in timed relation so that the projecting portion on one roller enters the 110 grooved portion on the other with the material to be torn passing between them, the grooved rolling member being adapted to make more than one revolution to form a complete article and having part of its pattern 115 overlapping upon another part.

2. The combination in a severing device of rollers provided with cooperating severing means, one of said rollers having part of its pattern overlapping upon another part in 120 such manner that complete severing is effected only after more than one revolution thereof.

3. A device for forming and dispensing 125 seat covers from a strip of material comprising a flap-severing means arranged in the design of an unclosed loop, an end severing means to partially sever one seat cover from another, a backing member for the severing means having grooves corresponding to the 130

design of the severing means, and means for frictionally holding the material over said grooves on both the front and rear sides thereof.

5 4. Seat cover forming means including co-operating rolls, male severing means on one of said rolls and arranged in such design as to sever a seat cover, the other roll having grooves to receive the male severing means
10 and of a design corresponding to the design of said means, said grooves being of a width comparatively greater than the width of said male severing means, and gripping means associated with one of the rolls and adapted to engage the seat cover material during the severing operation to prevent slippage thereof.

15 5. A device for forming and dispensing paper articles from a roll of paper the width of the articles equaling the width of the paper web, comprising a rotatably mounted, non-continuous end severing means for partially severing an article from the paper web, a backing member for the severing means, the 20 backing member being rotatably mounted and having grooves corresponding to the design of the severing means, means for frictionally engaging the paper in advance of the groove to draw it off the supply roll, and
25 means for frictionally holding it over said grooves on both the front and rear sides thereof.

30 6. Means for forming a paper article having V shaped ends from a web of paper, including cooperating rolls, male severing means on one of said rolls and arranged in such design as to sever from the web an article having V shaped ends, the other roll having spirally extending grooves to receive
35 the male severing means and of a design corresponding to the design of said means, said grooves being of a width comparatively greater than the width of said male severing means, and gripping means associated with
40 one of the rolls and adapted to engage the paper at a plurality of points spaced lengthwise of the roll and draw it between the rolls and to prevent slippage during the severing operation.

45 5. Signed at New York, in the county of New York and State of New York, this 22nd day of March, A. D. 1927.

ROBERT LAY HALLOCK.
